CIGARETTE AND CIGAR HOLDER ATTACHMENT

Ada Deerf, Coney Island, N. Y.

Application April 13, 1939, Serial No. 267,573

1 Claim. (Cl. 131—174)

This invention relates to cigarette and cigar holders, and aims to provide an attachment therefor whereby a cigarette or cigar may be firmly clamped in and to the holder so that it 5 will not fall out of the holder at any time.

A further object is the provision of a split cylindrical attachment in cooperation with the above, to provide a container or receptacle into which the ashes may fall and be caught, thus 10 preventing falling of the ashes on to the floor, clothing, table, or other place. The latter may be used as a case for the holder when the latter is not in use.

Another object is the provision of a clip in 15 combination with the first-mentioned attachment, which serves to permit releasable securing of the holder in the pocket and also serves to cooperate with the second-named attachment to releasably lock the latter in position.

20 The above and other objects will become apparent in the description below, in which characters of reference refer to like-named parts in the accompanying drawing.

The drawing serves merely to illustrate one embodiment of the invention, and it is not intended 25 that the invention be limited to the details exactly as shown.

Referring briefly to the drawing, Figure 1 is a 30 side elevational view of a holder equipped with the cigarette locking attachment.

Figure 2 is an end view of Figure 1.

Figure 3 is a cross-sectional view taken on the line 3—3 of Figure 1.

Figure 4 is a side view of the cylindrical container per se.

Figure 5 is a similar view showing the container applied to the holder, partly in section.

Figure 6 is a cross-sectional view taken on the line 6—6 of Figure 4.

40 Figure 7 is a cross-sectional of the lower container section taken on the line 7—7 of Figure 5.

Referring briefly to the drawing, the numeral 45 10 indicates a cigarette holder having an annular groove 11 around its wider end. The attachment comprises a split ring or band 12, similar to that of a common fountain pen pocket clip, the fingers 13 and 14 of which resiliently engage the holder. From the band 12 a tongue 15 extends unitarily forward, then angularly upward through a length 16, then again forward through a greater length 17, the level of the length 17 being the same as that of the lowest point of the opening 18 of the holder 10. The tongue, forward of the section 17, is doubled back 50 and under the latter to form an extension 19, being thus provided between the sections 17 and 18.

An extension 20 extends at right angles from the section 17, and is doubled back and over to form a resilient finger 21 having a rounded end section or jaw 22 and an upwardly turned extremity 23.

The tongue 15 and its sections 17 and 18 form an ordinary pocket clip, by means of which the holder may be secured in upright position to the 10 wall of a pocket, in an obvious manner. To insert a cigarette, the extremity 23 is first slightly lifted to lift the rounded jaw, the cigarette is then inserted between the jaw 22 and the section 17 into the opening 18 of the holder. The 15 jaw 22 is then released, and its resiliency causes it to press the cigarette down against the section 17, thus firmly clamping the cigarette and preventing it from falling out of the holder.

The container attachment shown in Figures 4 20 and 5 and 6 comprises a cylinder formed of two complementary sections 24 and 25, the latter having a ring 26 at its outer end, and the two sections being mutually hinged together at 27. The outer end 28 of the container is closed and 25 the inner end 29 is partly open. The lower edge of the inner end of the section 24 curves upward, as shown at 30, and is provided with an opening 31 to form a yoke 32 at its extremity. A U-shaped resilient member 33 is secured in any 30 desired manner about the yoke 32, and extends outward from the container. The container may be releasably and securely attached to the 35 holder attachment by slipping the member 33 into the recess 19, as shown in Figure 5. Thus, the 35 container may be used to catch the ashes either in closed position or in the open position shown in broken lines in Figure 5. The cover section 25 of the container may be provided with air vents 34. When not in use, the holder may be placed 40 within the container, in which event the latter provides a case for the holder.

For the sake of clarity, the jaw 22 has been shown spaced at a greater distance from the holder mouth 18 than would be desired in actual 45 practice, but whatever this distance may be would not alter the invention in any way.

Obviously, modifications in form and structure may be made without departing from the spirit and scope of the invention.

I claim:

An attachment for a cigarette or cigar holder comprising a resilient band adapted to encircle the holder and frictionally lock thereon, a tongue extending forward from the bottom of said band 55

and in front of the mouth of the holder, a doubled up and back resilient finger extending at right angles from said tongue, said finger having a rounded jaw spaced above and facing said tongue, a cigarette or cigar inserted into said mouth of the holder being resiliently clamped by said jaw against said tongue, said tongue having a doubled back and under extension forming a resilient

5 pocket clip, an elongated container having a yoke at one end, a member extending outward from said yoke and integral therewith, said member being adapted to register in said clip to secure said container to said holder, said container being adapted to enclose said cigarette or cigar.
